IRON-CHROMIUM TITANIUM BASE ALLOYS

Schuyler A. Herres, Albany, and Thomas K. Redden, Cohoes, N. Y., assignors to Allegheny Ludlum Steel Corporation, Brackenridge, Pa., a corporation of Pennsylvania

No Drawing. Application February 8, 1950,
Serial No. 143,148

11 Claims. (Cl. 75—175.5)

This invention relates to new and improved titanium-base alloys containing iron and chromium and a hardening element of the type of oxygen and nitrogen and particularly, to a titanium-base alloy which has greatly improved tensile and yield strengths, adequate ductility for hot and cold forming, excellent corrosion resistance, and which may be reversibly hardened or softened by proper heat treatment.

This application is a continuation-in-part of our application, Serial No. 118,723 entitled "Titanium Alloys" and filed September 29, 1949.

An alloy of the type here involved is particularly suitable for structural uses, such as aircraft engines, frames, turbines, etc., where higher strength and light weight are essential. The alloy has a substantially uniform crystalline structure that can be fully developed by hot and cold working operations and heat treatment. It also has a high corrosion resistance, particularly against sea water and chloride solutions.

An object of our invention has been to provide titanium-base alloys for structural purposes having a good load carrying ability and sufficient ductility for working, etc.

The constituents of the alloys fall within the following exemplary ranges:

TABLE I

A

	Per cent
O	.02 to .50
Fe	.75 to 7
Cr	1.5 to 14

B

	Per cent
N	.05 to .25
Fe	.75 to 7
Cr	1.5 to 14

C

	Per cent
N	.02 to .25
O	.02 to .50
Fe	.75 to 10
Cr	1.5 to 20

For optimum results in alloy A, the iron should be a minimum of about 2 times the oxygen content and not substantially less than and about $\frac{1}{2}$ the amount of chromium content (at least about 1 iron to 2 chromium). The oxygen is used within a range permissible and is proportioned to the chromium and iron to provide hardening without excessive hardness.

For optimum results in alloy B, the iron should be a minimum of about 4 times the nitrogen content and not substantially less than and about $\frac{1}{2}$ the amount of chromium content. Like the oxygen of A, the nitrogen is used within a range permissible and is proportioned to the chromium and iron to provide hardness without excessive hardness.

2

In alloy C, where both oxygen and nitrogen are used, their ranges are substantially the same as where they are used separately, see alloys A and B. The lower limits of the iron and chromium are substantially the same as before, but their upper limits are slightly greater, although the $\frac{1}{2}$ to 1 ratio is maintained for optimum results.

The following alloys represent alloys within the ranges of Table I which distinguish from each other from the standpoint that the second set A₂, B₂ and C₂ make possible the retention of a body-centered lattice structure:

TABLE II

A₁

	Per cent
O	.02 to .50
Fe	.75 to 3.0
Cr	1.5 to 6.0

B₁

	Per cent
N	.10 to .25
Fe	.75 to 3.0
Cr	1.5 to 6.0

C₁

	Per cent
O	.02 to .50
N	.02 to .25
Fe	.75 to 3.0
Cr	1.5 to 6.0

A₂

	Per cent
O	.02 to .50
Fe	4.0 to 7.0
Cr	8.0 to 14.0

B₂

	Per cent
N	.05 to .20
Fe	4.0 to 7.0
Cr	8.0 to 14.0

C₂

	Per cent
O	.02 to .50
N	.02 to .25
Fe	4.0 to 7.0
Cr	8.0 to 14.0

The following is representative of properties attained in an alloy of the type here involved which has been forged and annealed at temperatures in the range of 1200°—1600° F. for one hour, and cooled in air:

TABLE III

	Alloy Addition, percent				Hardness, BHN	Tensile Strength, p. s. i.	Yield Strength, p. s. i.	Elong., percent
	O	N	Cr	Fe				
1	.05	2.0	1.0	270	110,000	98,000	21	
2	.05	2.0	1.0	275	120,000	107,000	22	
3	.05	4.2	1.8	320	144,000	136,000	12	
4	.05	4.2	1.8	340	156,000	142,000	16	
5	.05	13.0	6.5	360	181,000	165,000	23	
6	.20	2.7	1.3	320	140,000	131,000	23	
7	.25	2.7	1.3	340	145,000	134,500	25	
8	.25	3.3	1.7	360	157,500	148,500	18	
9	.25	6.6	3.3	415	183,500	173,500	0	
10	.25	10.0	5.0	363	185,000	175,000	1	
11	.40	2.7	1.3	355	153,000	143,000	17	
12	.50	2.0	1.0	349	157,000	147,000	18	
13	.50	2.7	1.3	363	157,000	147,000	15	
14	.10	4.2	1.8	360	160,000	145,000	15	
15	.10	5.0	2.5	388	189,000	178,000	3	
16	.20	8.0	3.8	355	168,000	153,000	9	
17	.20	10.0	4.8	360	176,000	163,000	13	
18	.25	2.0	1.0	330	153,500	138,000	18	
19	.25	2.6	1.3	340	162,000	148,000	16	
20	.25	3.4	1.6	360	172,000	161,000	15	

Representative optimum oxygen-containing alloys of Table III, namely 1, 3, 6 and 8 to 13, inclusive, fall within the following range:

TABLE IV

	Per cent
O	.05 to .50
Fe	1 to 5
Cr	2 to 10

Representative optimum nitrogen-containing alloys of Table III, namely 14 to 20, inclusive, fall within the following range:

TABLE V

	Per cent
N	.10 to .25
Fe	1 to 4.8
Cr	2 to 10

Representative optimum oxygen and nitrogen containing alloys of Table III, namely 2, 4, 5 and 7, fall within the following range:

TABLE VI

	Per cent
N	.05
O	.05 to .25
Fe	1 to 6.5
Cr	2 to 13

The alloys may be produced in accordance with procedure set forth in our above-entitled co-pending application. They may be used in various conditions of heat treatment depending upon the specific properties desired. Alloys A₁, B₁ and C₁ respond favorably to heat treatment and may be hardened by rapid cooling, as water quenching from temperatures somewhat above 1350° F., or softened by relatively slow cooling from the same temperature.

TABLE VII

Examples of response of A, B, C type alloys to heat

Heat Treatment	.25% O, 2.7% Cr, 1.3% Fe		.25% N, .05% O, 2.7% Cr, 1.3% Fe	
	BHN Hardness	BHN Hardness	BHN Hardness	BHN Hardness
1,200° F., 1/2 hr. + water quench	334	301		
1,300° F., 1/2 hr. + water quench	343	331		
1,400° F., 1/2 hr. + water quench	390	372		
1,500° F., 1/2 hr. + water quench	462	440		
1,600° F., 1/2 hr. + water quench	450			
1,700° F., 1/2 hr. + water quench	473	550		
1,600° F., 1/2 hr. + air cool	340	330		

Alloys A₂, B₂ and C₂ respond favorably to heat treatment of a different type. That is, on heating to a temperature somewhat above 1400° F. and cooling at a rate that may be slower, the higher the content of chromium and iron or both of them, a high temperature body-centered cubic lattice structure characteristic of titanium at higher temperatures is stabilized and retained at room temperature. This produces a softer more ductile alloy than if the same alloy were cooled sufficiently slowly to transform it into a hexagonal, closely-packed lattice structure.

All of the alloys may be hardened somewhat by moderately rapid cooling from a temperature above about 1200° F., followed by an aging or precipitation hardening mechanism on reheating and holding for various periods within the temperature range of 500° to 1000° F. The time of holding is less, the higher the aging temperature in this range and the effect is reversible, so that the alloy may be softened again by reheating to a higher temperature.

All of the alloys may also be hardened by cold working,

as by mechanical reduction in cross-sectional area at temperatures below about 1200° F. and may be softened again by heating to temperatures above about 1200° F. for various periods, the temperature and time employed in the softening operation will depend on the degree of cold work accomplished. They may also be surface hardened as pointed out in the above-entitled co-pending application.

The small amounts of oxygen and nitrogen appear beneficial in improving the properties of the body-centered alloys A₂, B₂ and C₂. In these alloys, the body-centered structure is assured by water quenching where the alloys contain chromium from about 8 to 14% and iron from about 4 to 7%, although air cooling may be employed where the chromium or iron or both of them are in higher amounts of the ranges. For example, an alloy containing about .15% iron, about .02% nitrogen, about .1% oxygen, and about 10% chromium will retain the body-centered structure on water quenching, but not on air cooling; if the chromium content is about 14%, the structure will be retained on air cooling. An alloy of about 4.8% iron, 10% chromium with about .2% nitrogen and .1% oxygen will retain the structure on air cooling. It is thus seen that the combination of iron and chromium favors retention of the body-centered structure.

The alloys of our invention are economical from the standpoint of the chromium used and excessive hardness and non-uniform characteristics are avoided by maintaining the three alloying additions within the ranges specified and especially in this respect, such proportions are critical, and particularly as to the maximum percentages of the oxygen, nitrogen and iron.

From the above it will be apparent that the specified range of nitrogen has a comparable effect to the specified range of oxygen, that the maximum amount of nitrogen has to be maintained below that of a comparable amount of oxygen, and that this is also true when the two gases are used in combination in an alloy of our invention. As compared to alloy A which contains oxygen and has a minimum iron content of about 37 times the minimum oxygen content, alloy B which contains nitrogen has a minimum iron content of about fifteen times the minimum nitrogen content; the ranges of the iron and chromium are the same in both cases. However, when both gases are used, see alloy C, the minimum amount of iron is proportional by the first specified amount to either the minimum oxygen or minimum nitrogen content. In addition, the ranges of the chromium and iron are slightly greater than when either of the gases is used alone.

TABLE VIII

Results of comparative stress rupture tests

COMMERCIALLY PURE TITANIUM

[75,000 p. s. i. tensile strength]

800° F.	30,000 p. s. i.	Broke on Loading	39% Elong., 78% Red. Area.
800° F.	10,000 p. s. i.	340 Hrs.	17% Elong., 71% Red. Area.

Properties of discs such as would be used for jet aircraft compressor wheels:

TENSILE PROPERTIES FOR TITANIUM ALLOY DISCS

7-inch diameter titanium alloy (.15% O, 2.7% Cr, 1.3% Fe) ingot

Disc upset from a two inch square 5 inches high to one inch thick 6 inch diameter. Forging was done at 1700° F. on a 2000 lb. hammer in one heating. Disc was annealed for one hour at 1300° F. after forging. Standard $\frac{1}{4}$ inch diameter test specimens were taken from the chord and on a diameter at the center of the disc.

	Ultimate Strength	Elong. 1"	Red. Area
Chord 1-----	129,000	25	51
Chord 2-----	131,400	20	51
Center 3-----	131,000	24	58

12-inch diameter titanium alloy (.25% O, 2.7% Cr, 1.3% Fe) Ingot

Disc upset from 4 inch square $\times$ 7 inches high to 1 inch thick $\times$ 9 $\frac{1}{2}$ inch wide disc. Forging was done at 1700° F. on a 2000 lb. hammer in two heatings. Disc was annealed for one hour at 1300° F. after forging. Standard $\frac{1}{4}$ inch diameter tensile test specimens were taken at two ends and the center on a diameter of the disc. The two tensiles C₁ and C₂ from the center section were taken one above the other.

Edge 1-----	143,800	20	42.8
Edge 2-----	143,000	24	48.3
Center 1-----	141,200	19	41.6
Center 2-----	143,200	16	30

What we claim is:

1. A titanium base alloy which contains iron within a range of about .75 to 10%, chromium within a range of about 1.5 to 20%, at least one gas within the ranges specified from the group consisting of: oxygen about .02 to .50% and nitrogen about .02 to .25%; the balance titanium with incidental impurities, and the chromium, iron and at least one of the gases being essential elements with the titanium.

2. A titanium-base alloy for structural purposes consisting essentially of about .75 to 10% iron, about 1.5 to 20% chromium, at least one alloying gas within the ranges specified from the group consisting of: oxygen about .02 to .50% and nitrogen about .02 to .25%; the balance titanium; the iron being maintained within a minimum of about two times the oxygen content, about four times the nitrogen content, and within a ratio of not less than about one half the chromium content.

3. A titanium-base alloy for structural purposes having a minimum tensile strength after annealing of about

110,000 p. s. i. and which consists essentially of about .75 to 10% iron, about 1.5 to 20% chromium, at least one alloying gas within the ranges specified from the group consisting of: oxygen about .02 to .50% and nitrogen about .02 to .25%; and the balance titanium.

5. A titanium-base alloy suitable for structural purposes which contains iron within a range of about .75 to 7%, chromium within a range of about 1.5 to 14%, and at least one gas within the ranges specified of the group consisting of oxygen about .02 to .50% and nitrogen about .02 to .25%; and the balance titanium with incidental impurities.

10. 6. A titanium-base alloy suitable for structural purposes which contains iron within a range of about .75 to 10%, chromium within a range of about 1.5 to 20%, nitrogen within a range of about .02 to .25%, oxygen within a range of about .02 to .50%, and the balance titanium with incidental impurities.

15. 7. A titanium-base alloy suitable for structural purposes which contains iron within a range of about .75 to 3%, chromium within a range of about 1.5 to 6%, at least one gas within the ranges specified of the group consisting of oxygen within a range of about .02 to .50% and nitrogen within a range of about .02 to .25%, and the balance titanium with incidental impurities.

20. 8. A titanium-base alloy suitable for structural purposes which contains iron within a range of about 4 to 7%, chromium within a range of about 8 to 14%, at least one gas within the ranges specified of the group consisting of oxygen about .02 to .50% and nitrogen about .02 to .25%, and the balance titanium with incidental impurities.

25. 9. A titanium-base alloy suitable for structural purposes which contains iron within a range of about 1 to 5%, chromium within a range of about 2 to 10%, at least one gas within the ranges specified of the group consisting of oxygen within a range of about .05 to .50% and nitrogen within a range of about .10 to .25%, and the balance titanium with incidental impurities.

30. 10. A titanium-base alloy suitable for structural purposes which contains iron within a range of about 1 to 6.5%, chromium within a range of about 2 to 13%, oxygen within a range of about .05 to .25%, about .05% nitrogen and the balance titanium with incidental impurities.

35. 11. A titanium-base alloy consisting of from 2-5% chromium, from 1-2% iron, from .05-20% nitrogen and the balance titanium.
